UNITED STATES PATENT OFFICE.

JAMES SEMPLE AND WILKINSON CROSSLEY, OF BROAD BROOK, CONN.

APPARATUS FOR EXTRACTING DYES.

SPECIFICATION forming part of Letters Patent No. 236,265, dated January 4, 1881.

Application filed August 9, 1880. (No model.)

To all whom it may concern:

Be it known that we, JAMES SEMPLE and WILKINSON CROSSLEY, of Broad Brook, in the county of Hartford and State of Connecticut, have invented a new and Improved Apparatus for Extracting Dyes, of which the following is a specification.

The object of this invention is to provide an improved process and apparatus by means of which dye-stuffs can be more thoroughly leached and the extract be obtained free from dirt, fibers, and other foreign substances.

The invention consists of an upright cylindrical vessel containing horizontal perforated plates for supporting the dye-stuffs, and provided with pipes for introducing steam for boiling and drawing off the extract, and for forcing the extract from the vessel, provided, also, with conveniences for introducing the un-leached and removing the spent dye-stuff, and with suitable devices for ascertaining and regulating the condition of the extracting process.

Figure 1 is a vertical sectional elevation of the extractor on line *y y*, Fig. 2. Fig. 2 is a cross-section of the same on line *x x*, Fig. 1. Fig. 3 is an enlarged vertical sectional elevation of the discharge pipe and cap.

Similar letters of reference indicate corresponding parts.

In the drawings, A represents a portable cylinder, constructed of boiler-iron or other material capable of withstanding the necessary steam-pressure, supported on legs A' A', and having riveted or otherwise secured about its bottom discharge-orifice, *a*, a screw-threaded tube, B, which is closed by a screw-cap, B', and provided, also, with two man-holes, C C', respectively, through the upper one of which, C, the dye-stuff is introduced into the cylinder A to be leached, and through the lower one of which, C', the spent dye-stuff is withdrawn. These man-holes C C' are tightly closed during the extracting process by ribbed covers D D, that are held in place by screws D' D' passing through the tops of the yokes D'' D'', which are secured to the side of the cylinder A, and the joints between the man-hole flanges and the covers D D are made steam-tight by suitable gaskets b b.

In the top of the cylinder A is a suitable stuffing-box, E, down through which a steam-

pipe, F, is introduced that reaches to or into the discharge-orifice *a* at the bottom of said cylinder, and is open at its lower end, and has a number of lateral perforations, c c, near its lower end, for the escape of steam. This pipe F serves the purpose of conveying steam into the cylinder A, for making the dye extract, and of conducting the extract from said cylinder when the dye-stuff is leached. Fixed about 55 this pipe F, below the level of the lower man-hole, C', at suitable distances apart, are two laterally-extending supporting-disks, F' F', and on the same levels with them lugs G' G' are secured on the inside of the cylinder A. 60 These disks F' F' and lugs G' G' are designed to support the circular horizontal perforated plates G G, on the upper one of which the dye-stuff is thrown through the man-hole C, while the lower plate G being more finely perforated 65 than the upper one, serves to retain most of the finer particles of dye-stuff that may pass through the perforations in the upper plate G. These plates G G are constructed in segmental sections, as shown in Fig. 2, that they 70 may readily be removed, through the man-hole G', for cleaning, or so that the inside of the cylinder A may be reached to be cleaned.

Connected with the top of the pipe F by a T-coupling, H, are two pipes, I I', provided 80 with suitable valves I'' I'''. The pipe I is designed for the introduction of steam into the cylinder A, for extracting the dye, and the pipe I' being the discharge-pipe for the extract.

A steam-pipe, K, entered into the top of the cylinder A, and provided with a valve, K', serves to conduct the steam under pressure into the cylinder A, whereby the extract is forced from the cylinder A into suitable receiving-kettles for concentration or other treatment. Suitable gage-cocks L L, for ascertaining the quantity of liquid in the cylinders, and a safety-valve, M, are also attached to the cylinder A.

The process consists in introducing the dye-stuff through the man-hole C, upon the upper plate, G, and in introducing a sufficient quantity of water to cover said dye-stuff. Then the man-hole C is closed, and steam is introduced through the pipes I and F into the bottom of the cylinder A, the valve I''' being

closed, whereby the water in the cylinder is 30
boiled and the dye extracted from the dye-
stuff. By means of a cock, N, near the bottom
of the cylinder A, some of the dye extract is
5 drawn off from time to time and its quality
determined. When the leaching has contin-
ued for a sufficient time the valve I'' is closed
and the valves I''' K' opened, and steam under
10 suitable pressure at once introduced,
through the pipe K, on the surface of the ex-
tract within the cylinder A, with the effect of
forcing the said extract up through the pipes
F and I' into a receiving kettle or tank. (Not
15 shown.) When the extract is thus expelled or
drawn off the screw-cap B' and lower man-
hole cover, D, are removed and the spent dye-
stuff taken from the cylinder A.

In the usual method of extracting dyes the
dye-stuff is suspended in bags of coarse fab-
ric in a kettle of boiling water, and hence the
20 said dye-stuff, being so compacted, does not
yield all its dye in the ordinary process, nor
does it permit the thorough drawing of the
extract from it; and it is found, too, that the
25 extracts produced in this way are contaminated
with lint from the bags and dust and dirt from
the dye-stuffs, that work into the goods which
are dyed. In our process all these objections
are overcome, as the dye-stuff is loosely spread

and thoroughly exposed to the action of the 30
steam and water, and is thoroughly lixiviated
by the steam that forces the extract from the
cylinder, while no bags are used to produce
lint, and all dust and dirt settle in the dis-
charge-pipe B and the space in the bottom of 35
the cylinder A below the end of the pipe F.

Having thus described our invention, what
we claim as new, and desire to secure by Let-
ters Patent, is—

1. An improved apparatus for extracting 40
dyes, constructed substantially as herein shown
and described, consisting of cylinder A, pro-
vided with bottom discharge-orifice, a, and tube
and cap B B', man-holes C C', with adjustable
covers D D, steam-heating and extract-dis-
charging pipe F, having connected steam-in-
let pipe I, and discharge-pipe I', perforated
45 supporting plates G G, and steam-pressure
pipe K, as set forth.

2. In a dye-extractor, the combination, with 50
the cylinder A, of the segmental perforated
plates G G, substantially as and for the pur-
pose described.

JAMES SEMPLE.
WILKINSON CROSSLEY.
